UNITED STATES PATENT OFFICE.

BENJAMIN F. BROOKE SEWELL, OF CHULA, VIRGINIA.

MULTIPLE-PURPOSE QUICK-ACTING IMPLEMENT.

Application filed November 13, 1922. Serial No. 600,523.

To all whom it may concern:

Be it known that I, BENJAMIN F. BROOKE SEWELL, a citizen of the United States, residing at Chula, in the county of Amelia and State of Virginia, have invented certain new and useful Improvements in Multiple-Purpose Quick-Acting Implements, of which the following is a specification.

This invention relates to multiple purpose implements and has for an object to provide an implement of the hand or manual type of tool adapted for use as a wrench or for a number of other purposes as for instance a vise, a punch or the like, by the removal and replacement of jaw members.

A further object of the invention is to provide an improved type of quick acting movement whereby the jaws may be caused to engage the work quickly.

20 A further object of the invention is to provide a type of implement wherein one of the jaws is released from the operating mechanism for manual movement and is re-engaged with great force produced by improved type of mechanical movement.

In the drawings:

Figure 1 is a view of the implement with one side forming a cover removed showing the internal construction of the mechanically movable parts.

Figure 2 is a sectional view taken on line 2—2 of Figure 1.

Figure 3 is a sectional view taken on line 3—3 of Figure 1.

Figure 4 is an edge view of the lever and pawl separated.

Figure 5 is a view in side elevation with half of the casing removed of a slightly different embodiment of the invention.

40 Figure 6 is a view similar to Figure 5 with the lever in open position and the rack and pawl disconnected.

Figure 7 is a transverse sectional view taken on line 7—7 of Figure 5.

45 Figure 8 is a transverse sectional view taken on line 8—8 of Figure 5.

Figure 9 is a view of the pawl and lever disconnected, seen from the position as of the top of Figure 5.

50 Figure 10 is a detail view in side elevation of the lever.

Figure 11 is a fragmentary detail view of a still slightly different modification.

55 The implement referred to may be made in several different forms. The embodiment as shown at Figures 1 to 4 inclusive com-

prises two substantially complementary spaced members 10 and 11 which are of general plate construction, having inturned flanges 12, 12', 13, 13' and 14, 14'. 60

The working parts comprise a lever 15 fulcrumed upon an integral stud 16 and having an offset 17. A rib or boss 18 is formed upon the lever 15 for properly positioning it between the spaced plates 10 65 and 11.

A pawl indicated as an entirety at 19, is provided with a head 20, preferably substantially cylindrical in form but for the purpose of milling provided upon nearly 70 diametrical sides with recesses 21. The pawl 19 is provided with a shoulder 22 properly proportioned and positioned to engage against a pin 23 when the lever 15 swings upon the stud 16 in the direction 75 indicated by the arrow. A spring 24 bears at one end against the top of the pawl 19 and at its opposite end against the flange 13 and is held in position by an embraced stud 25. This spring tends to force the pawl 80 downwardly into engagement with the sliding jaw 26. The pawl 19 is provided with a plurality of teeth 27, properly proportioned to engage interacting teeth 28 on the sliding jaw so that, when the lever 15 is 85 moved to closing position, the teeth 27 engage the teeth 28 and move the sliding jaw in the direction indicated by its arrow.

The sliding jaw 26 is provided with a recess 29, and a bowed spring 30 is set into the recess, the ends being engaged by the sliding jaw within the recess and the central or bowed portion bearing yieldingly against the plate 11, as indicated more particularly at Figure 3. The sliding jaw 26, 95 as will be noted especially from Figure 3, is provided with grooves 31 traveling upon the flanges 12 and 12', and a stud 32 is interposed in the path of movement, manually removable so that by removing said 100 stud the sliding jaw may be removed and replaced. At their extremities, the plates 10 and 11 have clamped between them a jaw member 33 held by a pin 34 likewise manually removable so that both the sliding jaw 105 26 and the jaw member 33 may be conveniently removed and replaced by co-acting jaw members of like or different type. As shown in the drawing, the jaw members are only such as might be reasonably used for 110 purposes of a wrench or a vise, but it is to be understood that other jaw members

for use as pipe wrench, shear, punch or the like may be substituted.

The plates 10 and 11 are spaced by spacing sleeves 35 and 36 through which bolts 5 or rivets 37 and 38 respectively are inserted.

A spring 39 is provided bearing against a lug 40 on the lever 15 and held in any approved manner as by the rivet 41 tending to move the lever 15 in the direction indicated by its arrow. A latch 42 is also provided, pivoted at 43 and adapted to engage the end 44 of the lever 15.

In operation, the lever 15 being released by the manual unlatching of the latch 42, 15 the spring 39 forces such lever upwardly upon its pivot 16 in the direction indicated by the arrow. This movement draws back the pawl 19, provision being made so that the teeth 27 may slip over the teeth 26 in 20 the return movement and the movement continued until the shoulder 22 engages the pin 23 whereupon a continued and further movement lifts the pawl 19 clear of the sliding jaw 26. In this position, the jaw 25 26 is free to be moved manually and may be slidably moved until it engages against the nut or other work whereupon the return movement of the lever causes the pawl to engage by the action of the spring 24 30 after the shoulder 22 is released from engagement with the pintle 23, and the further movement causes the sliding jaw 26 to grip with great power against the work. When used as a wrench this engagement may be 35 maintained by the hand of the user or, when used as a vise or the like, the latch 42 may be brought into use.

As shown at Figures 5 to 10 inclusive, a modification of the invention is disclosed 40 wherein the stud 16' serves as a stop for the pawl 19', as disclosed more particularly at Figure 6. It will also be noted that in this modification the lever 15' is mounted upon the same side of the body as the 45 sliding jaw 26'. This sliding jaw is preferably provided with a removable and replaceable pipe face 45. As shown at Figures 5 and 6, a socket is provided in the sliding jaw 26' to receive the shank of the pipe 50 jaw 45 in working position, as shown at Figure 6, with a different socket for receiving it in idle position as shown at Figure 5. The stationary jaw is likewise provided with means for co-acting with either 55 the plane face of the jaw 26' or the pipe face 45. This comprises a sleeve 46 having upon one side a pipe jaw face 47 and upon the opposite side a plane face 48. This sleeve 60 46 is removable and replaceable upon the body and is held by means of a spring 49, having a lug 50 engaging in openings 51 upon opposite sides of this sleeve. By depressing the lug manually, the sleeve 46 may be removed from the body and reversed so that either the plane face 48 or the

pipe face 47 is in position for co-acting with the sliding jaw 26 either in its plane face condition or its pipe jaw condition, as shown respectively at Figures 5 and 6.

As shown at Figure 11, an auxiliary jaw 70 52 is provided, slidable upon the flanges 12' independently of the sliding jaw 26''. Upon one side, this sliding jaw 26'' is provided with a pipe face 53 and the auxiliary jaw 52 is provided with a pipe face 54. Upon the opposite side, the auxiliary jaw is provided with a plane face 55 and the rigid jaw is provided with a plane face 56 for co-acting therewith. The auxiliary jaw member 52 may be slidably movable therefore into engagement either with the fixed jaw to utilize its pipe face or into engagement with the sliding jaw to utilize its plane face whereby the device is at all times equipped for operating either as a plane nut 85 wrench or as a pipe wrench.

It will be understood that all of these several sliding jaws 26, 26' and 26'' are interchangeable and may be used upon any of the several types of bodies shown in the 90 several figures; also that the auxiliary jaw 52 is capable of use in conjunction with any of the bodies as shown or any of the jaws properly equipped for operating therewith. In other words, it is to be understood that 95 all of the features in regard to the sliding jaw and its actuating means, consisting of the rack with the plurality of complementary teeth, the various utilities of and carried by the sliding jaws and the auxiliary 100 jaw are common to all of the several types shown.

The relation of the several parts, especially the moving parts of this implement, is particularly emphasized. It will be noted 105 that the arc of travel of the center of the pivoting of the pawl 19 or 19' is short because of its proximity to its fulcrum and that it varies but little from parallelism with the line of travel of the sliding jaw; 110 also that this center of pivoting of the pawl is but slightly removed laterally from this line of travel whereby the force from the leverage is applied to the traveling jaw in the most advantageous manner corresponding as nearly as may be to the direction of movement of the sliding jaw. The laws of leverage will, of course, make it at once apparent that the relation of the pivot point of the pawl to the fulcrum of the lever is 115 such that the force is very greatly multiplied and by applying this force with the smallest possible angle the greatest efficiency is provided.

Further efficiency is provided in the shape 125 of the teeth of the rack of the traveling jaw and the pawl, said teeth being relatively large and, therefore, resisting in an augmented degree wear and liability of breakage. This advantage is further augmented 130

by providing the pawl, as will be noted, with a considerable number of teeth so that the stresses applied by the great leverage are divided among the several contacts.

5 With the pawl made long as is desirable to carry the plurality of teeth of the size just mentioned, it is obvious that the angle of application of force will be less than would be the case if the pawl were shorter 10 and provided with a lesser number of teeth. While the present invention is not limited to any specific angle, it has been demonstrated that an angle of not more than thirty degrees will apply the forces of the leverage to the sliding jaw with nearly the maximum efficiency.

In operation, therefore, the pawl being positioned as shown at Figure 6 or in dotted lines in Figure 1, the sliding jaw is free 20 to be moved manually. This may be accomplished by grasping the jaw itself in the particular type shown at Figure 1 or by the use of the hooked end or finger hold 57, as shown at Figures 5 and 6. Usually the 25 manual movement applied thus directly to the jaw will be to open the jaw as the closing action is brought about by a continued oscillation of the handle. For the moving of the jaws forward, it is obviously not necessary that the handle be moved to its 30 releasing limit as the spring will permit the pawl to slide along the rack of the jaw so that only a limited oscillation of the handle will result in a step by step forward 35 movement of the sliding jaw. By moving the handle to its releasing limit of oscillation, the jaw may be moved in either direction. With the auxiliary jaw in place, it will be obvious that the manual moving of 40 the jaw to open the jaw interval will permit the manual sliding of the auxiliary jaw in either direction to bring it into operative contact with either the fixed jaw or the sliding jaw whereby either a plane wrench 45 or a pipe wrench is provided.

As has been pointed out, the utility of the device is not limited to a wrench as, by reason of the great leverage, the device is also

operable as a hand vise. The adaptation of the device to other uses where power of 50 movement of a sliding jaw is desired will be obvious to one skilled in the art.

What I claim to be new and desire to secure by Letters Patent is:

1. An implement comprising a body having spaced side walls, a lever pivoted between the side walls upon a pivot fixed relative to said walls, a jaw slidable relative to the walls and provided with a rack, a pawl, means pivoting the pawl to the lever 55 eccentric of the pivot, and means carried by the pawl for engaging the pivot of the lever for throwing the pawl out of engagement with the rack.

2. An implement comprising a body having spaced walls, a lever pivoted between the walls upon a pivot fixed relative to the walls, a jaw slidable relative to the walls and provided with a rack, an offset formed upon the lever eccentrically relative to its 60 pivot, a pawl pivoted to the offset and provided with means for engagement with the rack, and means carried by the pawl for engagement with the pivot of the lever at one limit of its movement, tending to throw 65 the pawl out of engagement with the rack.

3. An implement comprising a body having spaced side walls, a lever pivoted between the walls upon a pivot fixed relative to the walls, a jaw slidable in the body and 70 provided with a rack, an offset formed upon the lever eccentric of the pivot, a pawl pivoted upon the offset and provided with means for engagement with the rack, means carried by the pawl positioned to engage 75 the pivot of the lever at one limit of its movement to throw it out of engagement with the rack, a spring tending to hold the pawl in engagement with the rack, and a spring adapted to actuate the lever to move 80 the lever to the limit of its movement against the tension of the spring controlling the pawl.

In testimony whereof I affix my signature.

BENJAMIN F. BROOKE SEWELL.
